UNITED STATES PATENT OFFICE.

JAMES M. DODGE, OF PHILADELPHIA, PENNSYLVANIA, ASSIGNOR TO THE DODGE COAL STORAGE COMPANY, OF SAME PLACE.

APPARATUS FOR UNLOADING BOATS.

SPECIFICATION forming part of Letters Patent No. 410,883, dated September 10, 1889.

Application filed December 3, 1888. Serial No. 292,515. (No model.)

To all whom it may concern:

Be it known that I, JAMES M. DODGE, of Philadelphia, in the county of Philadelphia and State of Pennsylvania, have invented a new and useful Improved Apparatus for Unloading Boats; and I do hereby declare that the following is a full, clear, and exact description thereof, reference being had to the accompanying drawings, making part of this specification.

My invention relates to certain new and useful improvements in apparatuses or contrivances for conveying or removing coal and other analogous materials from the barge or vessel in a river to any requisite destination or locality on land—as, for instance, to the proper elevation for discharge either into storage-bins or into railroad - cars for transportation.

To enable those skilled in the art to which my improvements relate to make and use the same, I will now proceed to describe my invention, referring by letters to the accompanying drawings, which form a part of this specification, and in which I have shown so much of the working apparatus or contrivance as is necessary to fully illustrate the several features of improvement made by me.

In the drawings, Figure 1 is a partial side view or elevation of a contrivance made according to my invention. Fig. 2 is a similar view with the chain conveyer and some other devices omitted for the sake of simplicity, and illustrating by dotted lines certain adjustments of the floating parts and their dependencies, to be hereinafter referred to. Fig. 3 is a view similar to Fig. 1, but with some of the mechanism omitted for the sake of simplicity, and showing by dotted lines certain adjustments or changes in the positions of the parts different from the adjustments illustrated at Fig. 2. Fig. 4 is an end view of the apparatus shown in side elevation at Fig. 1, looking in the direction indicated by the arrow at the last-mentioned figure. Fig. 5 is a partial top view of the apparatus shown in side view at Fig. 1. Fig. 6 is a detail view, on an enlarged scale, of the winding-drum.

In the several figures the same parts will be found designated by the same letters of reference.

A represents the lower portion of an obliquely, arranged ordinary conveyer-trough, which is permanently arranged relatively to and rests upon the beach or shore *a* of the river or other piece of water in which are supposed to be the boats or barges from which it is desired to extricate or carry off the coal or other material to be handled. This inclined ordinary conveyer-trough is supposed to extend upwardly in the direction indicated by the arrows (see Figs. 2 and 3) onto the shore and to a sufficient extent, if necessary, to assist in the conveyance of the coal or other material to a suitable elevation either for its discharge by gravity into storage-bins or into the cars of transportation railroad-trains.

B is an adjustable extension-trough, which is constructed after the fashion of any ordinary conveyer-trough, but which is supported at its inner end upon suitable wheels *c*, which rest and travel upon the upper edges of the stationary trough A, this end of the said extension-trough B being adapted to slide immediately over and partially within the depression of the stationary trough A. This adjustable extension-trough B, which is designed to extend about horizontally out over the surface of the water, (which is illustrated by broken lines at *w*), has its outer end suspended and supported by means of a suitable float D in the following manner: Said float D is made of any suitable size, shape, and material, and is formed or provided with a superstructure or frame-work *d*, and the extension-trough is provided with a bail-like metallic upwardly-projecting frame *e*, from the apex of which an ascending and supporting cable-chain *f* passes over a sustaining pulley or sheave *g*, the axle of which is mounted in suitable stands *h*, arranged on the upper part of the frame-work *d* of the float. Said chain passes thence about horizontally to and partially around another sheave or chain-wheel *i*, that is similarly supported by suitable stands *j*, and descends thence to a winding-drum *k*, the shaft of which is mounted in suitable bearing-boxes secured to the lower portion of the frame-work *d* of the float, all as clearly shown. The shaft of this winding-drum is provided, preferably, with a worm-gear, with which en-

gages a suitable worm, the shaft of which is provided, as shown, with a crank-handle *m*, by means of which it can be turned in one direction or the other to either wind up the 5 chain *f* upon the drum *k* or to let it out therefrom, as occasion may require. This float *D*, with its superstructure and the mechanism for supporting at any desired elevation the outer portion of the extension-trough *B*, is located far enough within the extreme outer 10 end of such extension-trough to permit the free passage beneath the outer portion of said trough of the barge or vessel (roughly illustrated at *T*) from which it may be desired to 15 remove the material to be handled, and this barge or vessel having been brought to the proper location widthwise relatively to the outer portion of the extension-trough *B*, said extension-trough has its outermost portions 20 adjusted vertically by the mechanism on the float *D*, just above described, so as to bring the trough as close down to the upper surface of the barge as practicable, so that the coal or other material in the vessel or barge may 25 be shoveled by hand directly from the barge into the said extension-trough *B*; and as the vessel or barge lightens by the partial removal of its cargo, and consequently rises in the water, the outer portion of said extension-trough is now and then lifted or elevated accordingly by the suspended and elevating mechanism just referred to.

Within the extension-trough *B* travel, in the usual manner, the flights of the lower run 35 of an ordinary chain conveyer, the outer turn of which chain conveyer travels around an ordinary sprocket-wheel *p*, the shaft of which is mounted in suitable bearings in a stand *q*, that is secured to and is supported by the 40 outer end of said extension-trough. This ordinary chain conveyer has its upper run supported at suitable intervals by idlers *r*, as clearly illustrated at Fig. 1, that are supported by the extension-trough *B*, and the 45 latter may also be provided near its inner end with an improved device for supporting the upper run, as shown at *s*, (see Fig. 1,) that is made the subject of another application of mine, Serial No. 292,516, filed December 3, 50 1888, and need not be particularly described herein. The said conveyer chain is supposed to be continued, of course, in the direction indicated by the arrow at the left-hand side of Fig. 1 to practically the same extent to 55 which the permanent conveyer-trough *A* may extend in the same direction, and has the flights of its lower run, after they leave the inner end of the extension-trough *B*, arranged to work within the ascending portion 60 of the stationary conveyer-trough *A* in a manner well known to those skilled in the art.

The object and effect of the arrangement of the inner end of the extension-trough *B* so as to slide longitudinally partially within 65 and on top of the stationary trough *A* are to permit any desired adjustment of the extension-trough *B* endwise that may be necessary

to accommodate said extension-trough and the position of its supporting-float *D* to any rise and fall of the water over which the extension-trough is supported and in which the vessels or barges have to be brought to anchor for the discharge of their cargo, and of course it will be understood that whenever the extension-trough *B* has to be either slid out or 70 drawn farther inland the endless-chain conveyer *o* has to be correspondingly let out and taken up. One of the means by which this must be done constitutes the subject-matter of another application by me filed simultaneously with this one, Serial No. 292,516, in which will be found fully described one way of effecting the taking up and letting out of the conveyer-chain. Supposing, for instance, 75 that the tide of the river (illustrated by broken lines at *w*) is high at Fig. 1, and understanding that the parts of the apparatus and also the barge are all shown in proper relative condition in said figure, it will be understood that in the event of the lowering of the tide, 80 so that the barge *T* would have to be brought up for discharge to a locality more distant from the shore, under such changed conditions (as to the tide and the necessary location of the barge *T*) the float *D* would have 85 to be placed farther away from the shore and the extension-trough *B* run farther out, it and the float maintaining about the same level relatively to the water. This movement or adjustment of the parts is illustrated at Fig. 3, where the dotted lines are 90 supposed to represent the float *D*, the extension-trough *B*, and the barge *T* in the same positions in which these parts appear at Fig. 1, but in full lines in a changed position, such as necessitated by the exigency just above 95 mentioned. In effecting this adjustment of the apparatus for the changed position of the barge *T* the inner end of the extension-trough *B* slides down easily slightly within and immediately over the permanent conveyer-trough *A*, its supporting-wheels *c* facilitating the 100 movement of the heavy structure in this manner and in the requisite direction, and at the same time, of course, the endless-chain conveyer *o* (which, as before remarked, must be 105 made distensible and contractible) is sufficiently let out to permit the necessary movement of the combined devices.

During the operation of unloading the 110 boat or barge *T*, no matter in what adjustment endwise the extension-trough *B* may be, said extension-trough, as before remarked, is adjusted vertically at its outermost portion, so as to maintain said portion in close proximity to the upper part of the barge as the latter may rise or fall, according to the condition of its cargo, and in performing the unloading operation the barge is of course, as usual, moved back and forth endwise, so as 115 to relieve it of its contents in a proper manner, said barges usually being of considerable length in proportion to their width.

It will be understood, of course, that by the

use of an apparatus or contrivance such as I have herein shown and so far described the shoveling of the coal from the interior of the barge into the extension-trough B can be very 5 conveniently accomplished by reason of the close proximity which can be maintained of said trough to that portion of the barge at which the shoveling operations may have to be conducted, and it will also be seen that by 10 virtue of the distensible and contractible endless-chain conveyer, in combination with the telescopic trough, or, in other words, with the stationary trough and its longitudinally-adjustable extension, a great variation in the 15 position relatively to the shore of the barges T is permissible without in the least affecting the perfect efficiency of the continuously-operating and automatic devices for conveying the material shoveled directly from the 20 barge into the extension-trough B off and upwardly to any desired elevation or distance. Of course, in the mere details of construction of the various parts and devices many 25 modifications and changes may be made without departing from the novel features of my improved contrivance or apparatus for unloading boats or barges and conveying the coal or other material therefrom to any desired locality on the shore. 30 As is well known to those familiar with the subject of handling coal and other material to be delivered on shore from vessels, it frequently happens at places where the bed or bottom is shallow and the rise and fall of the 35 water considerable that a great variation occurs with reference to the point to which, relatively to the shore and stationary devices, the barge can be brought for the discharge of its cargo, and in such cases my improved apparatus possesses marked advantages over 40 and greater efficiency than any contrivances heretofore devised that I know of.

Having now so fully explained the general construction and mode of operation of my 45 improved apparatus that those skilled in the art can make and use the same, embodying either all or only some of the features of my improvements, what I claim as new, and desire to secure by Letters Patent, is—

50 1. In an apparatus or contrivance for dis-

charging coal or other material from vessels or barges to a given point or locality on shore while the said vessels or barges may be at variable distances from and at different levels relatively to the point of discharge of the 55 material, the combination of the following instrumentalities, arranged and operating together in substantially the manner hereinbefore specified, viz: first, a stationary conveyer-trough extending from the point of discharge of the material down into the water; second, a movable conveyer-trough extension having its inner end movably supported within the said stationary conveyer-trough; third, a suitable float for supporting the high- 60 65 most portion of said trough-extension in close proximity to and parallel with the deck of the barge or vessel to be unloaded, and, fourth, an endless chain provided with flights which travel within and convey the material 70 shoveled from the hold of the vessel into the extension-trough, along through the latter, and also thence upwardly through the stationary conveyer-trough.

2. In combination with the stationary conveyer-trough extending down into the water, a conveyer-trough extension bearing at one end on and both longitudinally and pivotally movable relatively to the stationary trough, and a conveyer-chain having its flights arranged and operating within said stationary trough, and also within said movable trough-extension, substantially in the manner and for the purposes hereinbefore set forth.

3. In combination with the stationary inclined conveyer-trough, a horizontal branch or extension thereof bearing at one end thereon and longitudinally and pivotally movable relatively thereto, and a conveyer-chain operating in conjunction with said extension of 80 85 said stationary trough, means for vertically supporting the outer end of said extension, substantially as and for the purpose hereinbefore set forth.

In witness whereof I have hereunto set my 95 hand this 13th day of October, 1888.

JAMES M. DODGE.

In presence of—

E. M. TURNER,
M. GETZ.
